Specification for Design.

Patented July 20, 1915.

Application filed August 3, 1914. Serial No. 854,883. Term of patent 14 years.

To all whom it may concern:

Be it known that I, HARRY H. LABADIE, a citizen of the United States, and a resident of the city of Chicago, in the county of Cook and State of Illinois, have invented a new, original, and ornamental Design for Luncheon-Tables; and I do hereby declare that the following is a specification thereof, reference being had to the accompanying drawing, forming a part hereof, in which the figure is a perspective view of a luncheon table showing my new design.

Copies of this patent may be obtained for five cents each, by addressing the "Commissioner of Patents, Washington, D. C."

I claim—

The ornamental design of a luncheon table as shown.

In testimony whereof I have hereunto set my hand in the presence of two subscribing witnesses.

HARRY H. LABADIE.
